UNITED STATES PATENT OFFICE

159,297

AIRPLANE SEAT

Harbert D. Rowe, Glendale, Calif., assignor to
Lockheed Aircraft Corporation, Burbank, Calif.

Application February 23, 1949, Serial No. 1,023

Term of patent 14 years

(Cl. D15—8)

To all whom it may concern:

Be it known that I, Harbert D. Rowe, a citizen of the United States of America, residing at Glendale, in the county of Los Angeles, State of California, have invented a new, original, and ornamental Design for Airplane Seat, of which the following is a specification, reference being had to the accompanying drawings, forming a part thereof.

Figure 1 is a side view of the seat of my invention in its normal forward facing position;

Figure 2 is a side view similar to Figure 1 showing the seat with its back reversed, the end standard having been omitted for convenience of illustration;

Fig. 3 is a front view of the seat when in the normal position as shown in Fig. 1.

Fig. 4 is a side view similar to Fig. 1 but showing the back in the fully reclined position.

Fig. 5 is a top plan view of the seat as shown in Fig. 1.

Fig. 6 is a perspective view with the back shown in a partially reclined position.

The characteristic features of my design reside in those portions shown in full lines in the drawing, which are shaded for contrasting appearance.

I claim:

The ornamental design for an airplane seat, substantially as shown and described.

HARBERT D. ROWE.
